UNITED STATES PATENT OFFICE

90,457

DESIGN FOR A DRAPERY OR THE LIKE

Max Sadinoff, Brooklyn, N. Y.

Application July 1, 1933. Serial No. 48,613

Term of patent 3½ years

To all whom it may concern:

Be it known that I, MAX SADINOFF, a citizen of the United States, residing at 1766 Union Street, in the borough of Brooklyn, city of New York, county of Kings, and State of New York, have invented a new, original, and ornamental Design for a Drapery or the like, of which the following is a specification, reference being had to the accompanying drawing, forming a part thereof.

The figure is a plan view of a drapery showing my new design. The broken away portion indicated by the dotted line shows a continuation of the design illustrated along the edge of the drapery, the body portion thereof showing no ornamentation.

The cross hatching appearing on the drawing represents the background of the fabric.

I claim:

The ornamental design for a drapery or the like as shown, and described.

In testimony whereof I have signed this specification.

MAX SADINOFF.
